(57) **CLAIM**

The ornamental design for an impedance measurement system component, substantially as shown and described herein.

DESCRIPTION

FIG. 1 is a front, top, and first side perspective view of a first embodiment of an impedance measurement system component embodying the new design;

FIG. 2 is a front view thereof;

FIG. 3 is a top view thereof;

FIG. 4 is a first side view thereof;

FIG. 5 is a second side view thereof;

FIG. 6 is a front, top, and second side perspective view thereof;

FIG. 7 is a bottom view thereof;

FIG. 8 is a back view thereof;

FIG. 9 is a front, bottom, and first side perspective view thereof; and,

FIG. 10 is a back, bottom, and second side perspective view thereof.
